UNITED STATES PATENT OFFICE.

JOHN W. TRIPP, OF SEDALIA, MISSOURI, ASSIGNOR OF ONE-HALF TO
ROBERT N. MARROW, OF SAME PLACE.

TOY.

SPECIFICATION forming part of Letters Patent No. 441,720, dated December 2, 1890.

Application filed July 18, 1890. Serial No. 359,174. (No model.)

To all whom it may concern:

Be it known that I, JOHN W. TRIPP, a citizen of the United States, residing at Sedalia, in the county of Pettis and State of Missouri, have invented a new and useful Toy, of which the following is a specification.

This invention has relation to that class of toys known as "musical whirligigs" or "buzzes," and the objects of the invention are to provide an exceedingly cheap toy of the above class, said toy being adapted to be easily manufactured and when operated to make a musical sound.

With the above objects in view the invention consists in certain features of construction hereinafter specified, and particularly pointed out in the claim.

Referring to the drawings, Figure 1 is a perspective of a buzz constructed in accordance with my invention. Figs. 2 and 3 are sections, the former being taken through the series of radial openings and the latter through the sound-passages.

Like numerals of reference indicate like parts in all the figures.

In practicing my invention I construct the buzz wholly of wood and of spherical shape, the same being turned in any convenient manner desired.

The sphere 1 is provided at intervals with a series of radially-disposed sound-openings 2, said series being arranged in the same line around the periphery or circumference of the sphere and communicating at the center of the sphere.

Disposed at a right angle to the series of openings 2 is a single radiating induction-opening 3, which communicates with the series at the center of the sphere. The sphere at each side of the outer end of the induction-opening 3 is provided with a dovetailed recess 4, and in the same is mounted a reed-plate 5, having a reed 6.

A pair of perforations 7, arranged parallel to each other and at each side of the axial center of the sphere, is formed therein, and through the same is passed the ends of the

operating-cord 8, which ends are secured together.

In operation the buzz is operated in the usual manner—viz., by first twisting the cords at each side of the buzz, and then intermittently tightening and loosening the same, so that the buzz is rapidly rotated in alternate directions. As the buzz revolves, the opening 3 causes a suction, and a current of air is constantly drawn through the single opening 3 and through the reed, which latter is thereby sounded and affords amusement.

I am aware that numerous devices of the above character have been heretofore invented; but they have all been so complicated in their construction as to render their cost too great for them to become popular. By my invention, however, by forming them of a sphere of wood, bored, as shown, the cost is greatly reduced, attractiveness increased, and none of the amusing qualities sacrificed.

Having thus described my invention, what I claim is—

As an article of manufacture, the herein-described spherical wooden buzz provided with a series of radiating openings intersecting each other at the center of the sphere, a single radiating hole disposed at a right angle to the series of openings and communicating therewith at their intersecting point, and opposite perforations located at diametrically opposite sides of and extending parallel to the single opening, the sphere being provided at the outer end of the single opening with a dovetailed recess, a reed-plate slid therein and provided with beveled edges, and an endless operating-cord passed loosely through the parallel perforations, substantially as specified.

In testimony that I claim the foregoing as my own I have hereto affixed my signature in presence of two witnesses.

JOHN W. TRIPP.
